UNITED STATES PATENT OFFICE.

JOHN F. O'CONNOR, OF CHICAGO, ILLINOIS, ASSIGNOR TO WILLIAM H. MINER,
OF CHAZY, NEW YORK.

FRICITION DRAFT-RIGGING.

1,361,485.

Specification of Letters Patent.

Patented Dec. 7, 1920.

Application filed February 16, 1920. Serial No. 358,990.

To all whom it may concern:

Be it known that I, JOHN F. O'CONNOR, a citizen of United States, residing at Chicago, in the county of Cook and State of Illinois, have invented a certain new and useful Improvement in Friction Draft-Riggings, of which the following is a full, clear, concise, and exact description, reference being had to the accompanying drawings, forming a part of this specification.

This invention relates to improvements in friction draft riggings.

The object of the invention is to provide a high capacity combined spring and friction draft rigging and one wherein the springs are located outside of the sills so that the usual space allotted within the sills may be utilized for the friction elements.

In the drawings forming a part of this specification, Figure 1 is a top plan view of a portion of a railway draft rigging showing my improvements in connection therewith. Fig. 2 is a longitudinal vertical sectional view taken substantially on the line 2—2 of Fig. 1. Fig. 3 is a vertical transverse sectional view taken substantially on the line 3—3 of Fig. 1. And Fig. 4 is a detail perspective of one of the friction end wedges employed with my arrangement.

In said drawing, 10—10 denote channel shaped center or draft sills of a railway car spaced the usual distance apart and having their flanges turned outwardly in the usual manner. A portion of a drawbar is indicated at 11 to which is operatively connected a yoke 12 of well known form. The improved draft rigging proper, as shown, comprises, broadly, the following elements; a front wedge A; a rear wedge B; a pair of laterally movable friction shoes C—C; front and rear fixed keys D—D; laterally extending springs E—E on the outer sides of the sills; outer spring followers F—F; inner followers G—G; upper and lower sets of plates H and I; and front and rear upper and lower sets of fixed plates or stops J—J.

The friction end wedges A and B are of similar form and each is provided with a pair of diverging friction wedge faces 13—13 and with an elongated recess 14 to

accommodate a key D. The latter are mounted in slots provided in the webs of the draft sills in such a way that the keys D are prevented from longitudinal movement. The keys D are held against accidental lateral displacement by any suitable means such as the cotters 15. The arrangement of wedges A and B and keys D is such that the front wedge A may move inwardly from normal position but not outwardly 60 with respect to the front key D and the rear wedge B may move forwardly from normal position but not rearwardly, with respect to the rear key D.

The laterally movable friction shoes C 65 are in the form of cast blocks each having oppositely beveled end friction faces 16—16 adapted to coöperate with the faces of the wedges A and B. On their outer sides, each shoe C is provided also with a longitudinally extending flat friction surface 17, the latter coöperating with the inner faces of the followers G.

Each of the followers G is preferably in the form of a relatively short section of 75 channel and the same is also true of the spring followers F—F. Each follower G is connected with the follower F more remote therefrom by means of either the plates H or the plates I. The plates I are two in 80 number and are comparatively wide, the same straddling the draft sills 10 and riveted at their ends to the flanges of the followers F and G. The plates H are four in number arranged in upper and lower 85 pairs and also in front and rear sets, the plates H being riveted to the flanges of the corresponding followers F and G. As will be apparent from an inspection of Fig. 2, the plates I are slidingly mounted between 90 the plates H or telescoped with respect thereto. The plates H are in turn slidingly mounted between the fixed plates J which are riveted to the draft sills. With this construction, it is evident that the followers F and G and the plates H and I are restricted to movement at right angles to or 95 transversely of the draft sills.

The springs E are preferably four in number, two on each side of the draft sills. 100

They are arranged in twin and to properly center the springs, the draft sills and followers F may be provided with integrally formed offsets or bosses 18-18 as indicated 5 in Fig. 3.

As appears from Figs. 2 and 3, the yoke 12 straddles the friction elements but is confined between the upper and lower sets of plates H, I and J and is also confined 10 between the followers G-G.

The operation is as follows: Assuming an inward or buffing movement of the drawbar, the front wedge A will be forced rearwardly, the rear wedge B remaining stationary on 15 the rear key D. As the front wedge A moves rearwardly, the friction shoes C-C are spread laterally and longitudinal movement will also be imparted thereto as the same slide over the rear wedge B. Friction 20 will thus be generated between the wedges A and B on the one hand and the friction shoes on the other hand. At the same time, friction will be generated between the outer flat surfaces of the shoes C and the followers 25 G. The lateral movement imparted to the shoes C will be transmitted to the followers G so that the latter are separated, thereby forcing the spring followers F-F to be pulled inwardly toward each other, the compressing force being applied to the springs 30 at the outer ends of the latter in a direction toward the draft sills. The plates H and I are held against longitudinal movement by the fixed plates J, as will be understood.

With my improved construction, I am enabled to utilize all the space allotted between the draft sills for the friction elements and the springs are located in spaces not now generally occupied. The friction elements 40 may be all formed as castings and the remaining parts of the shock absorbing mechanism proper, with the exception of the keys, may be made from plates and channels ordinarily carried in stock.

45 I claim:

1. In a railway friction draft rigging, the combination with draft sills; of friction devices located between the sills and including longitudinally and laterally movable elements; springs disposed outside of the sills; and means, restricted to movement transversely of the sills, for transferring the movement of said laterally movable friction elements to the outer ends of said springs to 50 thereby compress the latter by forces directed inwardly toward the sills.

2. In a railway friction draft rigging, the combination with draft sills; of friction devices located between the sills and including longitudinally and laterally movable elements; springs disposed outside of the sills; and means, restricted to movement transversely of the sills, for transferring the movement of said laterally movable friction 55

elements to the outer ends of said springs to 65 thereby compress the latter by forces directed inwardly toward the sills, said means including upper and lower sets of plates slidingly telescoped and extending from between the sills to points outside thereof. 70

3. In a railway friction draft rigging, the combination with draft sills; of laterally extending springs located outside of the sills and held against movement lengthwise of the sills; friction devices located within the 75 sills; spring followers at the outer ends of the springs; oppositely and laterally movable means interposed between said followers and the friction devices whereby action of the latter is communicated to the springs; 80 and means preventing longitudinal movement of said laterally movable means.

4. In a railway friction draft rigging, the combination with draft sills; of friction devices including laterally movable elements 85 located between the sills; laterally extending springs disposed outside of the sills; and means for compressing said springs upon actuation of the friction devices including loops, each loop encircling the laterally movable friction elements, a sill, and a spring. 90

5. In a railway friction draft rigging, the combination with draft sills; of laterally arranged springs disposed on the outer sides of the sills; spring followers disposed at the 95 outer ends of said springs; friction devices located between the sills; followers disposed on opposite sides of the friction devices and located between the sills; and telescoping sets of upper and lower plates, each set connecting one of said followers between the sills with the more remote spring follower 100 outside of the sills.

6. In a railway friction draft rigging, the combination with draft sills; of laterally arranged springs disposed on the outer sides of the sills; spring followers disposed at the outer ends of said springs; friction devices located between the sills; followers disposed on opposite sides of the friction devices and 105 located between the sills; telescoping sets of upper and lower plates, each set connecting one of said followers between the sills with the more remote spring follower outside of the sills, said plates straddling the sills; and 110 fixed means coöperating with the plates to prevent longitudinal movement thereof.

7. In a railway friction draft rigging, the combination with draft sills, a drawbar, and yoke-acting means; of friction devices disposed between the sills and including front and rear relatively longitudinally movable wedges and laterally movable friction elements; stop-acting means coöperable with said friction devices; laterally arranged 115 springs on the outer sides of the sills; spring followers at the outer ends of the springs; a follower located between each of said later- 120 125

ally movable friction elements and the corresponding adjacent sill; upper and lower plates connecting each said follower disposed between the sills with the spring fol-
5 lower outside of the sill more remote there-
from, said plates being slidingly telescoped with respect to each other; and front and rear upper and lower sets of plates rigidly

secured to the sills and between which said first named plates are slidingly guided. ¹⁰

In witness that I claim the foregoing I have hereunto subscribed my name this 7th day of Feb., 1920.

JOHN F. O'CONNOR.

Witness:

CARRIE GAILING.
